UNITED STATES PATENT OFFICE.

JOHN S. SHUCK, OF FULLERTON, NEBRASKA.

DRAFT-EQUALIZER.

SPECIFICATION forming part of Letters Patent No. 393,272, dated November 20, 1888.

Application filed May 7, 1888. Serial No. 223,154. (No model.)

To all whom it may concern:

Be it known that I, JOHN S. SHUCK, of Fullerton, in the county of Nance and State of Nebraska, have invented a new and useful Improvement in Draft-Equalizing Stays, which improvement is fully set forth in the following specification and accompanying drawings, in which—

Figure 1 is a top or plan view of my improved draft-equalizing stays for eveners and whiffletrees; Fig. 2, a view of the clip attached to the pole of a vehicle to support the grooved pulley; and Fig. 3, a view of the grooved pulley, the hollow stud, and the disk to which it is attached, the recess in the clip to receive the same, and the wedge-shaped washer for adjusting the disk.

The object of my invention is to provide improved draft-equalizing stays to be adjustably attached to eveners and whiffletrees, and designed to increase their efficiency and usefulness by staying and supporting them in all their relative positions, and securing perfect equality of draft, without interfering with the freedom of their movement within prescribed limits, and arresting the motion at any desired point without racking or straining. My device also provides means for transferring the draft directly from the whiffletree to the evener, thereby obviating the downward and forward tendency of the former, the twisting of the latter, and the danger of fracture of the bolt uniting the two, in consequence of the transverse strain upon the same. These results are secured by the mechanism illustrated in the accompanying drawings, in which—

A designates a swivel composed of two segments united at their ends, the outer segment having a tongue to engage the groove in a pulley, B, which is pivoted to the pole of a vehicle at a suitable distance rearwardly of the evener C. The said swivel is approximately one-fourth of a circle described by a radius which is found by taking the distance between the center of the pulley and the point where the stay-rods are attached to the segment.

The rear ends of the stay-rods D are attached to the end of the swivel by screw bolts and nuts and by means of apertures in the ends of the swivel, the series of which extends on a

line toward the center of a circle of which the segment composes a part. The stay-rods may be shifted obliquely backward or forward, thus increasing or diminishing the length of the swivel between them, by which means the swing of the evener to which the forward ends of the stay-rods are attached may be also increased or diminished at pleasure, the play of the swivel on the pulley being limited to the interior semicircular ends of the swivel engaging the pulley.

To provide means for attaching the pulley firmly but adjustably to the pole, so that the swivel may oscillate on a plane corresponding with that of the evener, I employ a clip, E, attached to the pole in the usual manner, having on top a rim forming a cup or recess to receive the disk F, centrally upon which is a hollow stud, G, which serves as a pivot for the pulley. If the pole be bent, a wedge-shaped washer, G', may be inserted under the disk in such a position as to effect the proper adjustment of the disk and pulley on the desired plane. By this arrangement it will be seen that the traction of the stay-rods is borne by the disk and its bearing on the forward part of the rim. The bolt H is thus relieved from the strain and serves merely to hold the parts in engagement.

The whiffletree I is attached to the evener by a clevis, J, secured by a bolt and nut in the usual manner. An integral hollow stem or sleeve, K, extends rearwardly from the bow of the clevis, and is tapped to engage the threaded end of the stay-rod, the length of which is thus made accurately and readily adjustable. The peculiar form of the clevis and the manner of attaching the same to the stay-rod obviates the tendency of the whiffletree to tilt forward and thereby cause the twisting strain upon the evener.

It will be understood that the various parts of my device are to be constructed of the most suitable materials, and the size and proportions of the same are to be graded according to the uses to which they may be applied and the demands upon the strength of the parts.

What I claim as new is—

1. In draft-equalizing stays, a swivel, A, composed of two segments, the outer of which is tongued, combined with and rotating on a

grooved pulley adjustably pivoted on the pole or tongue of a vehicle, rearwardly of the evener or doubletree, substantially as herein set forth.

2. The segmental swivel A, adjustably connecting with the stay rods and combined with and rotating on a pulley adjustably pivoted on the tongue of the vehicle, substantially as described.

3. The combination of the clip having the grooved pulley, the swivel, the adjustable stay-

rods, and the doubletree, substantially as herein set forth.

In testimony that I claim the foregoing I have hereunto set my hand, this 5th day of December, 1887, in the presence of witnesses.

JOHN S. SHUCK.
